UNITED STATES PATENT OFFICE.

MARGARET JANE AMSDEN, OF WATERTOWN, NEW YORK.

THIMBLE THREAD-CUTTER.

SPECIFICATION forming part of Letters Patent No. 548,497, dated October 22, 1895.

Application filed June 22, 1895. Serial No. 553,700. (No model.)

To all whom it may concern:

Be it known that I, MARGARET JANE AMSDEN, a citizen of the United States, and a resident of Watertown, in the county of Jefferson and State of New York, have invented certain new and useful Improvements in Thimble Thread-Cutters; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a representation of a perspective view of invention applied. Fig. 2 is a section through thimble.

The object of this invention is to provide a thread-cutting attachment for sewing-thimbles, which can be readily applied to thimbles of the ordinary construction, whose formation is such that it is self-guarded or free from any point, hook, or projection of a nature which, through incidental or careless manipulation of the thimble, can catch in the work or scratch or abrade the skin, and which is convenient and effective.

With this object in view the invention consists in the novel construction and combination of parts, all as hereinafter described, and pointed out in the appended claim.

Referring to the accompanying drawings, the letter A designates an ordinary thimble, and B my improved thread-cutting attachment. Said attachment consists of a small thin blade having parallel lateral faces, whose planes are perpendicular to the periphery of the thimble, and which are perfectly smooth, with the exception of that portion of one face 40 which constitutes the cutter proper. The inner edge α of said blade from its lower end is straight to the point b , where is a small projection, which extends through an opening in the shell of the thimble, in which opening it 45 is firmly secured by being brazed, soldered, or, as shown, by having its inner end upset to form a rivet-head, which is filed off substantially flush with the inner surface of the said shell. The outer edge of said plate at its 50 lower portion is beveled down, as indicated at c , to meet the line of the inner edge α for the purpose of forming an acute point, which is

forcibly entered underneath the usual rim or flange f of the thimble. Above said beveled portion c the said outer edge is formed with 55 an inward offset d , from which it forms a convex curve e , which terminates at the point of a small projection g , which is extended above the upper edge h' of the blade. This upper edge portion, together with the inner edge of 60 the projection g , is beveled upon one face to form the cutting edges of the device, an oblique notch for the thread being usually formed where the two beveled surfaces meet.

It will be observed that the maximum 65 point w of the curve e is at or near the base of the projection g , and that above this point the said curve approaches the periphery of the thimble, whereby the point of said projection is considerably inside of a line x tangential to the said maximum point of the curve e and touching the periphery of the thimble at the point z ; or, in other words, if such line be considered as representing a surface upon which the thimble rests the only 70 points of contact with such surface will be at the points w and z . It will be apparent, therefore, that the said projection is guarded by the said curve from catching into the work or into the skin.

75 The shoulder formed by the inward offset d forms an abutment for the tool employed in forcing the point of the device into engagement with the rim or flange f of the thimble.

In use the thimble is placed on the finger 85 with the attachment at the back and the thread is cut by moving the finger downward over the thread, which is held firmly.

Having thus described my invention, what I claim as new, and desire to secure by Letters 90 Patent, is—

The combination with a thimble, of the herein described thread cutting attachment therefor, said attachment consisting of a small metallic, parallel-faced, blade having the 95 point at the lower end which engages the base rim or flange of the thimble, the inward projection at its upper inner edge which is secured in the shell of the thimble, and the pointed projection g at its upper outer portion, which projection extends beyond the upper edge of the blade in the plane thereof and which, together with the upper edge portion, is beveled upon one face to form the cut-

ting edges of the attachment, the outer edge of said blade having the convex curve *e* which terminates at the point of said projection and which from its maximum point at or near the base of such projection approaches the periphery of the thimble, whereby the point of the projection is brought considerably within a line tangential to the maximum point of the said curve and touching the circumfer-

ence of the thimble at its upper portion, substantially as and for the purpose specified.

In testimony whereof I affix my signature in presence of two witnesses.

MARGARET JANE AMSDEN.
